SEPARATOR DEVICE

Leo E. Rush, Lafayette, Ind., assignor to M. L. Joyce, Lafayette, Ind.

Application July 11, 1932, Serial No. 621,885

3 Claims. (Cl. 183—2.5)

The chief object of the invention is to provide means for filtering from the liquid such as gasoline the water and sediment that might be included therein, and collect the same in a sump which may be readily cleaned.

Another object of the invention is to eliminate the air that may be entrapped with the liquid being supplied under pressure before the liquid reaches the metering device and if the pump is equipped with a telltale device commonly known as a visi-gauge before the liquid reaches the latter.

Another object of the invention is to provide means whereby the meter, visi-gauge (if employed), and the hose, if the pump is of the so-called "wet hose" type, is full of liquid from which the air has been removed and from which all of the adulterants, such as water, grit and sediment, have been removed, and to maintain this liquid at substantially atmospheric pressure in the hose, visi-gauge, and the meter.

The chief feature of the invention consists in the employment of means suitable for accomplishing the aforesaid objects and a further feature of the invention consists in the association of the respective parts with an automatically initiated power operable dispensing pump structure.

The full nature of the invention will be more clearly understood from the accompanying drawings and the following description and claims:

Fig. 1 is a central sectional view of the upper portion of a dispensing pump equipped with the unit embodying the invention, a meter, the face of the same being shown in elevation and the pressure applying pump proper and the power means therefor being omitted, since these may be of a conventional character. Fig. 2 is an enlarged central sectional view through the unit. Fig. 3 is a transverse sectional view of the unit base and connections and is taken on line 3—3 of Fig. 2 and in the direction of the arrows. Fig. 4 is a view similar to Fig. 1 of a modified form of the invention. Fig. 5 is an enlarged sectional view similar to Fig. 2 but of the form of the invention shown in Fig. 4, parts being broken out to condense the figure.

In the drawings 10 indicates a suitable standard or casing within which is included the operating parts of a dispensing pump suitable for the dispensing of gasoline. In Fig. 1, the apparatus shown therein is not illustrated with the electric motor and pressure applying unit or pump connected thereto since these are conventional. The pressure applying pump has its intake communi-

cating with a pipe that extends to near the bottom of a storage tank, usually an underground one. The discharge from the pressure applying pump is connected to a pipe indicated at 15 in Fig. 2.

The casing supports a metering chamber 16 (see Fig. 1) upon which is mounted a meter structure 17 that operates the indicating fingers 18 and 19 and the counting wheel mechanism 20. The discharge from chamber 16 is connected by conduit 21 to the intake 22 of a telltale device commonly known as a visi-gauge of which there are several commercial forms now available. Said visi-gauge is indicated by the numeral 23. The discharge 24 therefrom connects to a flexible 15 hose 25 that terminates in a nozzle 26 which preferably is controlled by a hand valve at the nozzle. This is the so-called wet hose type of pump.

In the present form of the invention the casing 10 supports a head casting 27 and formed thereon is a socket 28 adapted to receive an end of the nozzle 26 as shown in Fig. 1. The head casting supports a light bulb socket 29 in bracket 30 and the head casting also supports a globe 25 or other advertising device 31 illuminated by the lamp or light bulb 32 mounted in the socket 29 and supplied with electric current through wires enclosed within the conduit 33a.

The hose nozzle when mounted in the socket 28, engages a lever arm 33 which is tilted thereby and through the rod 35 normally retains the electric switch for controlling the electric motor in open circuit position. Upon removal of the filling nozzle 26 from the socket 28, the lever 33 is released to its constraint and the rod 35 is moved thereby serving to close the electric circuit to the motor which immediately starts the pressure pump operating to supply liquid under pressure from the underground storage tank to the inlet 15 of the separator unit A to which this invention is specifically directed.

The unit A includes a lower chamber 40 and an upper chamber 41, the latter terminating in a dome 42. The dome has an outlet 43 and a 45 conduit 44 leads therefrom and preferably extends to the underground storage tank. Interposed in the conduit and as shown in Fig. 2, at the junction of the conduit with the dome is a normally open but restricted passage 45, the purpose of which will appear more fully hereinafter.

The chamber 41 is separated from the chamber 40 by a partition 46 having an opening 47 therein. Surrounding said opening and in spaced relation and extending upwardly from the par-

partition 46 is a cylindrical wall or well 48. A cylindrical screen 49 having a closed upper end 50 and an open lower end 51 is positioned in the opening 47 and the flange 52 of said open end 56 of the screen bears against partition 46. Said portion 52 also serves as a spring retainer and a coil spring 53 has one end bearing thereon, the other end bearing on a cap 54 detachably mounted in the open lower end 55 of a sump chamber 56. The cap 54 has depending therefrom a tubular extension 57, the lower end of which is closed by a cap screw or other member 58. The chamber 41 has a discharge outlet 59 below the level of the partition 46 and a conduit 60 extends from said discharge outlet 59 to the meter chamber 16 (see Fig. 1).

The operation of the device is as follows:

If the device be incorporated in an electric motor operable pressure applying pump, when 20 the nozzle 26 is removed from socket 28 the arm 35 initiates application of pressure and the supply of liquid under pressure to the unit, said liquid entering said unit at 15 and into chamber 40. The liquid changes direction upon entering chamber 40 and passes laterally therethrough and into the open mouth 51 of the screen 49. This screen serves to remove the water from the gasoline, which water being heavier than the gasoline, collects in the chamber 56. The change of 30 direction and also the screen, serves to remove the sediment from the gasoline, and said sediment also collects in the chamber 56. When it is desired to remove the sediment and water from the chamber 56, the closure 59 is removed from 35 conduit 57 and the water and sediment is allowed to escape and does so by gravity.

The liquid which passes through the screen, passes upwardly in the annular channel between the cylindrical wall 48 and the cylindrical screen 40 and over the top of said wall into the chamber 41. Since pressure is being applied to the liquid, 40 the level of the liquid will rise from that shown in Fig. 2 so that the liquid will completely fill the dome 42. When the level rises due to the application of pressure, the air trapped or included in the dome is forced therefrom and through the restricted port 45 and returned to the storage tank. All during the interval that liquid under pressure is supplied and following the discharge of all the air from the dome 42, liquid under pressure will be discharged through the restricted port 45. In other words, the pressure pump must handle a slight excess of liquid.

The aforesaid operation, therefore, insures that 55 no air is permitted to pass into the discharge line 60 and, therefore, into the meter chamber 16 and from there into the visi-gauge 23 and also the hose 25. Upon the cessation of pressure, the liquid in the event there is a leaky foot valve, will 60 never fall below the level of the top of the cylindrical wall 48 so that so long as the connections from the discharge line 59 to the valve controlling the nozzle 26 are all leak-proof, there will be no possibility of liquid leakage from the connections and, of course, no air entrapment because there will always be the same head of liquid determinable by the top of the wall 48 upon the liquid trap between the same and the valve in the nozzle 26.

70 It will be observed from Fig. 1 that the unit

is positioned at practically the highest point of the pump and it is also furthermore to be noted that the top of partition 46 is at an elevation above the upper level or elevation of the visi-gauge 23.

It will be clearly apparent also from Fig. 2 that when the screen requires cleaning, the cap 54 may be removed and with it will fall the spring 53 and the screen 49 and the only loss of liquid will be that included in chamber 40, sump 56 10 and that included within the wall 48 and below the top level thereof.

In Figs. 4 and 5 of the drawings there is illustrated a modified form of the invention which operates substantially as before set forth. In 15 said figures similar numerals of the one hundred series indicate like or similar parts. In this form of the invention the meter 116-117 is positively supported on plate bracket 100 anchored at 101, thus forming a relatively shock-proof 20 foundation. Also in this form of the invention the filter, vent and sump construction includes but one casting, part 140, the equivalent parts herein being formed of standard piping, these with part 140 replacing casting 40-42 of Fig. 1. 25 Also the meter has but one non-rigid or pipe connection that being indicated at 121. Furthermore, in this form of the invention the vent structure is interposed between the intake and filter (see Fig. 5) instead of between the outlet 30 and the filter (see Fig. 2).

In this form of the invention, cap 154 instead of being threaded to member 140 may be a stamping and is bolted thereto as at 155. The filter 149 rests upon seat 147 and is of a double character 35 149a indicating a #10 mesh reinforcing structure and 149b indicating a #100 mesh filter screen.

The invention claimed is:

1. In a separator device, the combination of a chamber having a normally open, valveless, vent 40 substantially at the highest point thereof, a tubular standpipe in said chamber terminating below said vent to form an air collecting space thereabove, the liquid flowing over the end of the standpipe and thereby permitting separation 45 of the entrapped air, a filter screen associated with the chamber and through which the liquid passes, a seat for said screen, a spring normally urging said screen to its seat, and a sump for collecting the screen separations including an 50 apertured closure for said sump, said closure being of sufficient area to permit screen removal for screen cleaning, and another closure for the closure aperture to permit sump discharge without screen removal.

2. A device as defined by claim 1, characterized by the apertured closure including an inwardly directed offset portion for spring seat purposes and a central well portion of lesser area 55 in which the aperture is located at substantially the lowest portion thereof.

3. A device as defined by claim 1, characterized by the apertured closure including an inwardly directed offset portion for spring seat purposes and a central well portion of lesser area 60 in which the aperture is located at substantially the lowest portion thereof, and by the closure therefor including an elongated tube, and a cap at the lowest end thereof.
